ADJUSTABLE GRAIN CHECK ATTACHMENT
FOR GRAIN BINDERS

Fredrick A. Mettler, Hutchinson County, S. Dak.

Application October 25, 1937, Serial No. 170,920

2 Claims. (Cl. 56—472)

This invention relates to improvements in adjustable grain check attachments for grain binders and more particularly to a device which may be readily attached to a self-binding harvester. As is well known in the art, the heads of wheat straws are heavier than the butt portions thereof, and consequently when feeding the unthreshed grain by gravity over the inclined surface of the deck or chute, to the binding and knotting mechanism of the harvester, the stems of the grain become disaligned, thereby resulting in an uneven or disarranged bundle. It has also been discovered that this unsatisfactory result is due to the varying lengths of the wheat straws.

However, the prior art devices, which have been adopted to overcome these objections have usually taken the form of tensioned fingers which normally rest upon the surface of the grain deck until raised out of engagement therewith by the completed bundles being forcibly moved thereagainst through the action of the usual ejector arms in discharging the bundle from the binding and knotting mechanism. The objection to the grain checks at present in use is that the latter, when suddenly released at the moment the bundle is discharged, fall with considerable force upon the grain deck and incoming wheat, thereby resulting in considerable loss of grain due to what might be termed a threshing action of the fingers. In order to overcome all of the foregoing objections, it is the primary important object of this invention to provide a grain check which is connected to the ejector mechanism, so as to operate in timed relation to the movements of the latter. A further important object of this invention is to provide a grain check of the above character which may be readily and quickly attached to the ejector mechanism of the grain binders at present in use.

A still further important object of this invention is to provide an adjustable grain check from which all tensioning means have been eliminated and which is positive in action.

A still further object of this invention is to provide a grain check of simple construction, and one which may be readily manufactured and placed upon the market at a reasonable price.

The foregoing and other objects and advantages of this invention will be apparent throughout the course of the following description and accompanying drawing, in which

Fig. 1 is a perspective view of a portion of a self-binder, with the adjustable grain check attached thereto,

Fig. 2 is a top plan view of the grain check

connected to a knotter shaft, a fragmentary portion of the latter being shown,

Fig. 3 is a sectional view taken on line 3—3 of Fig. 2, and

Fig. 4 is a side elevation of a modified form of the invention.

Referring in detail to the drawing, 1 designates the binder deck and 2 the butt-board. Associated with the deck in the usual manner is the binder frame 3 supporting the rotary knotted shaft 4, 10 tyer-wheel 5, breast-plate 6, ejector arm 7 and ejector arm supporting bracket 8, all of the foregoing parts being of the usual construction at present in use.

The instant invention pertains broadly to the 15 grain check attachment and its manner of connection to the usual self-binder, and more specifically consists of a right angle bracket member 9, formed to provide a short arm 10 and elongated arm 11.

The arm 10 is formed with a circular opening 12, and a spaced elongated slot 13 therethrough, said slot and opening extending in a direction parallel to the arm 11.

The arm 11 is provided with a transverse screw 25 threaded opening 14 adjacent to and extending at right angles to the opening 12 and slot 13, for the reception of a screw-threaded locking pin 15 which latter is of a length to be projected across the circular opening 12 for a purpose to be hereinafter more fully described. The free end of the arm 11 is further provided with a plurality of spaced aligned openings 16. A tapered rod-like finger 17 has its enlarged end provided with a plurality of longitudinally spaced openings 18, 35 and certain of which openings are to be aligned with certain of the openings 16 so as to receive a fastening member 19, whereby the finger 17 may be horizontally or vertically adjusted with respect to the free end of the elongated arm 11, 40 and to the grain deck 1 over which said finger is supported and moves.

In the modified form of the invention as disclosed in Fig. 4, the device consists of a channeled substantially rectangular body 20 formed 45 with an elongated slot 21 extending therethrough. Formed integral with said body and projecting beyond one end thereof is an extension 22, having its free end curved as at 23 to cooperate with a curved plate 24 which together form a shaft 50 engaging clamp, adapted to be secured to each other by means of a bolt fastener 25. The channeled body 20 is formed to receive and support one end of a tapered finger 26 which latter is secured to said body by means of threaded bolts 55

27, which extend through the slot 21 and openings (not shown) formed in said finger.

In attaching the preferred form of the invention, as disclosed in Figs. 1, 2, and 3, one of the 5 ejector arms 7, which is carried by the knotter shaft adjacent the free end of the latter, is removed from its supporting bracket 8. The right angle bracket member 9 is then placed on shaft 4 by passing the latter through the opening 12 10 until the outer face of the arm 10 abuts the bracket 8. The locking pin 15 is then turned down until its inner end engages with the knotter shaft, whereupon an additional fastening member 19' is passed through the bracket 8 and arm 10. 15 It will thus be seen that the bracket 9 is locked upon the knotter shaft in a manner so as to prevent relative longitudinal and transverse shifting of the parts. It will be further noted that, the 20 positioning of the finger 17 at right angles to the short arm 10 eliminates the necessity of aligning the parts when the brackets 8 and 9 are operatively connected, and places the free end of finger 17 in position to check the incoming grain after the ejector arms 7 have discharged a previously 25 completed bundle.

In connecting the modified form of the invention, as shown in Fig. 4, to the free end of the knotter shaft, the grain check is clamped about said shaft by the cooperating members 23, 30 24, and 25, so that the finger 26 will be disposed closely adjacent the grain deck with the ejector arms 7 extending rearwardly and spaced from said finger by substantially 90°.

From the foregoing, it will be seen that either 35 of the grain checks disclosed, is directly connected to the knotter shaft and rotates therewith and with the ejector arms 7, from which latter they are definitely spaced so as to move to a posi-

tion to check the incoming grain until same is gathered and tied immediately upon discharge of the previously completed bundle by said ejector arms.

While I have shown and described several forms 5 of my invention, it is to be distinctly understood that same may be further varied without departing from the spirit of the invention or the scope of the subjoined claims.

Having thus described my invention, what I 10 claim is:

1. A grain check attachment for use with a self-binding harvester having a grain deck and a rotary discharge arm shaft overlying said deck, including a right angle bracket member having 15 one of its arms formed with an opening and an elongated slot spaced from said opening, the other arms of said bracket having a plurality of spaced aligned openings therethrough, a rigid grain check rod having one of its ends provided 20 with a plurality of spaced openings therethrough for selective alignment with one of the openings through said other arm of the right angle bracket, and means received through said aligned openings in the bracket and grain check rod to secure 25 said members together.

2. A grain check attachment for self-binding harvesters, comprising a right angle bracket member having one of its arms provided with an opening, an adjustable fastening member carried by the other arm of said bracket member adjacent to and mounted for relative movement in a path transverse of the axis of said opening, an elongated rod and means to adjustably connect said rod to the free end of said other arm of the 30 bracket member.

FREDRICK A. METTLER.
